(57) **CLAIM**

The ornamental design of a searchlight and charging station, as shown and described.

DESCRIPTION

FIG. 1 is a front perspective view of our new design for a searchlight with charging station with the search light mounted in the charging station and a spare battery in a second charging station.

FIG. 2 is a front elevation view of FIG. 1.

FIG. 3 is a back elevation view of FIG. 1.

FIG. 4 is a left side elevation view of FIG. 1.

FIG. 5 is a right side elevation view of FIG. 1.

FIG. 6 is a top plan view of FIG. 1.

FIG. 7 is a bottom plan view of the searchlight shown in FIG. 1. The bottom surface of the base is shown in dotted lines and is not part of the claimed design.

FIG. 8 is a bottom plan view of the searchlight shown in FIG. 1, with the handle being shown in a rotated position.

FIG. 9 is a front elevation view of the searchlight with the charging station removed for ease of illustration.

FIG. 10 is a back elevation view of FIG. 9.

FIG. 11 is a left side elevation view FIG. 9.

FIG. 12 is a right side elevation view of FIG. 9

FIG. 13 is a top plan view of FIG. 9.

FIG. 14 is a front elevation view of the charging station with the flashlight removed for ease of illustration.

FIG. 15 is a back elevation view of FIG. 14

FIG. 16 is a left side elevation view of FIG. 14

FIG. 17 is a right side elevation view of FIG. 14; and,

FIG. 18 is a top plan view of FIG. 14.
